Primary Examiner — Katherine A Holbrow*Assistant Examiner* — Christopher M Spivey(74) *Attorney, Agent, or Firm* — Banner & Witcoff, Ltd.(57) **CLAIM**

The ornamental design for a display screen with icon, as shown and described.

DESCRIPTION

The FIGURE is a front view of a display screen with icon showing my new design.

The broken line shows a display screen and forms no part of the claimed design. The white space between the icon and the broken line forms no part of the claimed design.

1 Claim, 1 Drawing Sheet(56)
